UNITED STATES PATENT OFFICE.

ALBERT WHITE, OF WILLIAMSTOWN, NEW JERSEY.

LOSS-PREVENTING DEVICE.

1,378,747.

Specification of Letters Patent. Patented May 17, 1921.

Application filed October 2, 1920. Serial No. 414,242.

To all whom it may concern:

Be it known that I, ALBERT WHITE, a citizen of the United States, and a resident of Williamstown, in the county of Gloucester, 5 State of New Jersey, have invented new and useful Improvements in a Loss-Preventing Device, of which the following is a description.

My invention relates to loss preventing devices and has particular reference to a device of this character for association with a watch to prevent the latter from accidentally falling from the wearer's pocket.

A further object of the invention is to provide a watch attachment which serves as a protector for the watch to exclude dirt and other foreign matter therefrom as well as to obviate the danger of the watch falling from the pocket.

20 Further, the invention embodies a protector or case for the watch formed of rubber or other pliable matter having the entire area of its outer face formed with outstanding projections which engage in the 25 walls of the wearer's pocket and thereby prevent the watch from easily falling therefrom, these projections being so arranged as to constitute a cushion should the watch become accidentally dropped.

30 With the preceding and other objects and advantages which may become apparent from the following description, the invention consists of the construction and arrangement of parts to be hereinafter enlarged upon, claimed and illustrated in the 35 accompanying drawings, wherein,

Figure 1 is a rear elevation of the device associated with a time piece;

Fig. 2 is a view partly in elevation and 40 partly in cross section; and

Fig. 3 is a perspective of the device.

Referring in detail to the drawings, wherein like characters of reference designate corresponding parts throughout the 45 several views, the numeral 5 designates a circular sheet of rubber or other elastic material having its edges curved inwardly upon

itself to provide gripping flanges 6 which embrace the sides of the watch designated at 7. An opening 8 is provided in the flange 6 through which the winding stem of the 50 watch projects.

The outer face of the protector or holder is provided with outstanding teats 9 over its entire area which engage in the walls of 55 the wearer's pocket and thereby prevents the case or protector from moving in the wearer's pocket and holds the same against dropping therefrom.

These teats 9 in addition to preventing 60 the watch from riding out of the pocket or dropping therefrom constitutes a shock absorbing surface should the watch be accidentally dropped on its obverse side.

It is to be understood that the form of 65 my invention herein shown and described is to be taken as a preferred example of the same, and that various changes in the shape, size and arrangement of parts may be resorted to without departing from the spirit 70 of the invention or the scope of the subjoined claims.

Having thus described my invention, what I claim as new and desire to secure and protect by Letters Patent of the United States 75 is:

1. A device of the character described comprising an elastic casing adapted to embrace the back and sides of a time piece, and a plurality of outstanding teats formed on 80 the outer face of the casing adapted to engage the walls of a pocket to prevent the loss of the time piece therefrom.

2. A device of the character described comprising an elastic casing adapted to hold 85 a time piece therein, the entire area of the outer face of the casing being provided with outstanding pocket engaging elastic teats, said teats also constituting a shock absorbing surface to prevent breaking of the time 90 piece should the same become accidentally dropped.

ALBERT WHITE.
